UNITED STATES PATENT OFFICE

ALEXANDER E. BLOCK, OF ST. LOUIS, MISSOURI

SHOE

Application filed January 8, 1926. Serial No. 79,944.

My invention relates to improvements in shoes and has for its object to provide a shoe having a substantially flat receiving surface for the heel of the wearer, and accomplishes that result by the combination of a single leveling element with the parts of the shoes now in use.

The purpose of that flat receiving surface is to sustain the heel portion of the wearer's foot with its bones and flesh in, as nearly as possible, the relative positions they occupy when the naked foot is in contact with the ground, under the weight of the body. I hence produce a heel-receiving surface which is not cupped or concaved beneath the heel bone. I employ to that end, in combination with the usual shoe materials, a leveling element which is cheap, light and durable, the building of which in place does not interfere with the usual methods of manufacturing shoes, or the employment of the usual lasts and machines, and the use of which adds no appreciable element of cost to the completed shoe. The shoe embodying my invention 25 may have a flexible or reinforced shank.

Drawings

In the drawings—

Fig. 1 is a bottom plan view of the heel portion of a shoe embodying my invention, showing the leveling element in place, the outer sole being removed.

Fig. 2 is a longitudinal vertical mid-sectional view of the structure shown in Fig. 1 as contained in the completed shoe, taken on the line 2—2 of Fig. 1.

Fig. 3 is a transverse vertical view in section of the completed shoe, taken on the line 3—3 of Fig. 1.

Description

The shoe illustrated has a counter 4 which with its outer covering 5 and lining 6 constitutes what are commonly termed in the art "upper materials", and their lower edges, at the level of the lower face of the inner sole 6^a are drawn inwardly as shown in Figs. 2 and 3 and so secured as to form a cavity 7. It is above this cavity that the pressure of 50 the wearer's heel bone rests, and into which

the inner sole 6^a is usually cupped. In this cavity 7 I provide the leveling element A contoured as shown in the drawings, its bottom face being shown in Fig. 1, and its longitudinal construction in Fig. 2, while its 55 skived lateral wings are shown in Fig. 3.

When the shoe is completed this leveling element A is mounted with its upper face contacting with the lower face of the inner sole 6^a its lower face resting upon the upper face 60 of the outer sole 8 while at the sides the in-drawn edges of the upper materials are in place between the skived lateral wings 12—12 of the leveling element A and the lower face of the inner sole 6^a. The front and rear 65 edges of the element A rest as shown in Fig. 2, the rear edge in juxtaposition to the adjacent edge of the upper materials and the front edge of the element A in substantial alignment with the breast 9 of the heel 10, and with the rear edges of the welt 11—11. In shoes of the type which terminates the outer sole at the breast of the heel the element A will rest upon the top lift of the heel. 75

The leveling element A is arranged to be secured in place by nails 13 or other desired fastening means; should said element A be made of nail-resisting material such as metal, it will preferably have perforations to permit the passage of said nails. Said leveling element A may be made of any desired material capable of being contoured to perform the desired function; in practice I have used leather for this purpose. 80

The illustrated contour of the element A and the co-acting shoe materials may be altered in various ways without departing from my invention as defined in the claim of this patent. 85

While in standard shoe manufacture, there is an appreciable amount of cupping of the heel in the center due to the space between the inner edges of the upper materials, the cupping is not altogether confined to that 95 portion as the last is convex and the counter is much thicker at the side and bottom where it rounds the last (it must be thicker at this point in order to strengthen it), from which point it tapers inwardly to a thin edge. The 100

cavity formed between the indrawn edges of the upper materials varies in different shoes, the inner edges of the lining, counter, and upper leather terminating at various points in relation to each other. The combination of the convex last and the thickened portion of the counter makes the heel higher around the outer edges of the heel seat than it is at the point where the upper materials terminate. The welt also forms a hump at the forward portion of the heel of a welt shoe.

The wings 12—12 being thinner than the body of the leveling element A, and being beveled outwardly as shown, I produce a device that insures a substantially flat heel receiving surface not only at the central area filled by the thick body of the leveling element A, but extend that flat surface to the outer portion of the heel seat.

I claim:

The improvement in shoes comprising a shoe having indrawn edges of upper materials between the inner and outer soles arranged to form a cavity between said soles; and a leveling element arranged to insure a substantially flat heel-receiving surface at the mouth of said cavity, said leveling element having lateral wings extending beyond the inner edges of said cavity.

In testimony whereof I hereunto affix my signature.

ALEXANDER E. BLOCK.
